UNITED STATES PATENT OFFICE.

DAVID F. COLES AND JAMES H. LUCKHURST, OF RAHWAY, NEW JERSEY.

SPONGE-HOLDER FOR SLATE-PENCILS.

SPECIFICATION forming part of Letters Patent No. 247,616; dated September 27, 1881.

Application filed April 23, 1881. (No model.)

To all whom it may concern:

Be it known that we, DAVID F. COLES and JAMES H. LUCKHURST, citizens of the United States, residing at Rahway, in the county of Union and State of New Jersey, have invented 5 certain new and useful Improvements in Sponge-Holders for Slate-Pencils; and we do hereby declare the following to be a full, clear, and exact description of the invention, such as 10 will enable others skilled in the art to which it appertains to make and use the same, reference being had to the accompanying drawings, and to letters or figures of reference marked thereon, which form a part of this specification.

15 This invention has for its object to furnish an attachment for slate-pencils, for holding a sponge for erasing the pencil-marks from the slate.

It consists in a holder in one end of which 20 is formed a straight socket, which receives and retains the end of the slate-pencil, and in the other end of which is formed a bell-shaped socket, which receives and holds the sponge, and a spring fixed to the bowl or socket, so that 25 it will grasp and hold the sponge.

In the drawings, Figure 1 shows the holder applied to a slate-pencil. Fig. 2 shows the 30 sponge, having a compacted portion made ready to be slipped into the holder. Fig. 3 shows the sponge-socket, provided with a spiral spring arranged to receive and hold the sponge.

35 *a* is the holder, made, by preference, of soft rubber, so that it will, by its expansive and contractile properties, more readily receive and retain the pencil and sponge, and so that it may be also employed to erase lead-pencil marks.

The holder is provided in its smaller end *a'* 40 with a socket, *a²*, into which the end of the pencil *b* can be thrust. When made of soft rubber the socket *a²* is slightly smaller than, and so that it will expand to receive the end of, the pencil.

45 The larger end *a³* of the holder is provided with a socket or sponge-receiver, *a⁴*, which is flaring at its outer or open end, and is gradually contracted toward its inner end, so as to present a conical or bell-shaped space, into which a portion of the sponge *c* is compacted.

50 The sockets *a²* and *a⁴* are separated by a par-

tition, *a⁵*, which prevents the head of the pencil from being pushed against the sponge, and it also gives greater strength to the holder, especially when the latter is made of soft rubber.

C is the sponge, which has a portion of one side compacted, ready to be thrust into the socket *a⁴*. When dry the sponge can readily be compacted into a small neck, *c'*, which is jammed tightly into the socket. Being thus compacted it will not readily become wet when 60 the outer portion, *c²*, is saturated.

The sponge may first be specially prepared by forming a neck, *c'*, by wrapping it with thread, as shown in Fig. 3; but ordinarily such special preparation is not necessary. It is usually sufficient to compact a portion of the sponge and then push this compacted neck into the socket.

The body *c²* of the sponge projects laterally over the annular rim surrounding the open end 70 of the socket *a⁴*. The annular rim serves as a bearing and compressing means, whereby the sponge is held more firmly in place as it is moved over the surface of the slate, and by which the water may be easily pressed from the 75 central portion of the body *c²* outward to the surface.

f is a spring made from a single piece of wire and formed into a conical-shaped coil corresponding to the shape of and fitting into the 80 socket *a⁴*. The coils of the spring are arranged close to the wall of the socket. The spring is protected by, and when the sponge is inserted the coils are pressed firmly against, the wall 85 of the socket. The inner end of the wire composing the spring is bent vertically downward and enters a slot in the partition *a⁵*, and is made fast by a suitable pin. The outer end of the wire is carried outward horizontally from the upper end of the coil and into a small opening, *f'*, in the wall and near the outer end of the socket, where it is held loosely, so that it can have a slight movement back and forth in said opening. When the sponge-neck is pressed into the spring the coils expand outward and 90 draw the end *f'* inward. The coil is held firmly within the socket by the end *f'*, so that it cannot be drawn out of the mouth of the socket by any ordinary force exerted in erasing pencil-marks.

The smaller end of the holder a' , when made of soft rubber, is intended to be used as a lead-pencil eraser; or, if it be made of hard rubber, it can be provided with an annular soft-rubber ring, e , which is retained in place by any well-known means.

Having described our invention, what we claim, and desire to secure by Letters Patent, is—

10 A sponge-holder for slate-pencils, consisting of a head, a , provided in one end with the tubular socket a^2 , and in its opposite end with the inverted conical-shaped socket a^4 , separated from the socket a^2 by the partition a^5 , and the

spring f , formed into an inverted conical-shaped coil adapted to fit in and close to the wall of the socket a^4 , and having its inner end made fast in the partition a^5 , and its other end extended horizontally and held loosely in an opening in the side and near the outer end of the 20 wall of the socket a^4 , substantially as set forth.

In testimony whereof we affix our signatures in presence of two witnesses.

DAVID F. COLES.
JAMES H. LUCKHURST.
